UNITED STATES PATENT OFFICE.

AARON SANFORD CRAVEN, OF OAK LANE, PENNSYLVANIA.

SAWING MACHINE.

Application filed April 7, 1920. Serial No. 371,792.

To all whom it may concern:

Be it known that I, AARON SANFORD CRAVEN, a citizen of the United States, residing at Oak Lane, in the county of Philadelphia and State of Pennsylvania, have invented certain new and useful Improvements in Sawing Machines, of which the following is a specification.

My invention relates to improvements in sawing machines for the transverse cutting of standards such as piles, posts, tree trunks, etc.

The object of the invention is to provide a sawing machine of novel, simple and efficient construction which may be readily applied to and removed from standards to be cut and which may be quickly and easily adjusted into a position to insure a perfectly level or horizontal cut irrespective of any variation in the standard from a true vertical position or from a position extending at right angles to a level or horizontal plane.

The invention is particularly adapted for use in cutting off the upper ends of previously driven piles where the upper ends of the cut piles are to be perfectly level at a predetermined horizontal plane, and where the driven piles do not always occupy true vertical positions, and where the bodies thereof at or near the level where they are to be cut do not extend at right angles to the cutting level.

With the above and related objects in view, the invention consists in the novel construction, combination and arrangement of parts hereinafter described and claimed.

In the accompanying drawings, illustrating my invention,

Figure 1 is a side view, partly in section, of a sawing machine embodying my invention applied to a pile or standard for cutting the same.

Figure 2 is a detail of the indicator for indicating the position of the saw relatively to a part of the standard.

Figure 3 is a top view, partly in section, of the machine applied to the pile or standard.

Figure 4 is a transverse section through a part of the saw and its supporting and guiding means, on line 4-4 of Fig. 3.

Figure 5 is a view of the outer end of a part of the supporting bracket and a part of the adjustable frame thereon which carries the saw, showing pivotal connection between them.

Referring to the drawings, 2 designates a bracket comprising a long horizontal supporting bar 3, an arm 5 extending downwardly from a point near one end of the bar 3, an inclined brace bar 6 connecting the arm 5 and bar 3, a horizontally-extending transverse bar 7 connected at its central portion to one end of the bar 3 and being curved, as shown in Fig. 3 to fit against one side of a round pile or standard 8, and a horizontally-arranged transverse supporting and guiding bar 9 mounted on the bar 3 in spaced relation to the bar 7 and provided with brace arms 10 connecting it with the bar 7.

Screwed into and through one end portion of the bar 7 is a screw 11 having a head 12 on one end thereof, by means of which it may be manually turned, and having a swivel 13 on the other end thereof. The swivel 13 is permanently attached to one end of a chain 14 which is adapted to extend around and embrace the pile or standard 8 which is to be cut by the machine. The other end of the chain 14 is adapted to be connected to the end portion of the bar 7 opposite to the end portion carrying the screw 11; and the preferred means for thus connecting the normally loose end portion of the chain 14 is the hook 15 formed on the end of the bar 7 and to which any one of the links of the chain 14 may be applied, in accordance with the length of the chain 14 required to properly embrace the particular pile or standard to which the machine is attached, as will be hereinafter explained.

The lower end portion of the arm 5 carries a screw 40 which is screwed into and through the arm 5 and has a head 41 formed on one end thereof by means of which it may be turned by hand. The other end of the screw 40 is pointed, at 42, as shown. The pointed end 42 of the screw 40 is adapted to be forced into the pile or standard to which the bracket 2 is applied, and the flange or shoulder 43 is adapted to engage the pile or standard and limit the extent of penetration of the pointed end 42; and, when the screw 40 is thus engaged with the pile or standard, it is adapted to support the bracket 2 against downward tilting, as will hereinafter appear.

Mounted on the bracket 2 is an adjustable frame 16 which carries the saw 17 and a suitable motor 18 for actuating the saw.

- The motor herein illustrated is a reciprocating pressure fluid engine which may be of any approved type operated by any suitable pressure fluid, such as compressed air, steam or gas. The motor 18 includes a horizontally arranged cylinder 19, a piston 20 therein adapted to be reciprocated by the pressure fluid, and a rod 21 extending from the piston and out through one end of the cylinder 19.
- 10 The frame 16 herein illustrated is a casting comprising the motor cylinder 19, a pair of spaced parallel arms 22 extending horizontally from one end of the cylinder 19, and spaced cross bars 23 connecting the arms 22.
- 15 The opposing faces of the arms 22 have longitudinally-extending parallel guiding grooves or channels 24 formed therein for the reception of the lateral edge portions of a plate 25 which is slidably fitted to the
- 20 grooves 24 to be reciprocated therein. One end portion of the plate 25 is provided with an upwardly-extending lug 26 which is connected to the outer end of the piston rod 21, whereby when pressure fluid is supplied to
- 25 the motor 18 to actuate the piston 20, the slide plate 25 will be reciprocated within the grooves 24.
- Secured upon the end portion of the slide plate 25 away from the lug 26 by means of cap screws 27 is one end portion of the saw 17 which is arranged horizontally and provided with suitable cutting teeth 28 along one of its longitudinal edges. The saw 17 projects beyond the end of the frame 16 and it is reciprocated by and with the slide plate 25 to effect the cutting operations when the machine is in service.
- The outer end of the frame 16 is pivotally connected to the outer end of the bracket 2 by means of a pivot pin 29 and a bracket 30 embracing the same. The bracket 30 is secured to the outer end wall of the cylinder 19 which forms part of the frame 16, and the pin 29 is formed on the bracket 2 and projects upwardly therefrom and is provided with a flange or collar 31 to engage the bottom of the bracket and limit its downward movement on the pin 29. The frame 16 and the parts carried thereby may be readily removed from or replaced upon the bracket 2 by withdrawing the bracket 30 from and replacing it upon the pin 29. When the frame 16 is in place upon the bracket 2, the end portion thereof away from the pivot pin 29 rests upon the bar 9 which supports and guides the frame 16 and permits it to be moved back and forth on the pivot pin 29 from side to side of the bracket 2.
- 60 The end portion of the frame 16 carrying the motor 18 is provided with a handle 32 and the opposite end portion of the frame 16 is provided with side handles 33, as illustrated in the drawings. The frame 16 and parts carried thereby may be readily re-

moved from or replaced upon the bracket 2 by means of the handles 32 and 33; and the frame 16 may be readily moved from side to side on the pivot pin 29 by means of the handles 33.

Pivoted, at 34, to the central portion of the bracket bar 7 is an indicator arm 35 which is movable from the position shown by dot-and-dash lines in Fig. 2 to the position shown in full lines therein and back again, and which is adapted to be held by friction in the position to which it is moved. The upper end of the indicator arm 35 is in the same plane with the lower face of the saw blade 17, when the arm 35 is up in the position shown by full lines to indicate the plane through which the saw will make a cut when operated.

The operation of the machine is as follows:

The frame 16 is removed from the bracket 2, the indicator 35 is raised to the position shown by full lines in Fig. 2, and the curved central portion of the bracket bar 7 is placed against one side of the pile or standard 8 to be cut with the upper end of the indicator 35 in registry with a mark previously made on the pile at the plane or place where it is desired to cut the same. The chain 14 is then drawn around the pile in close engagement therewith and one of the chain links is engaged with the hook 15, the several links of the chain providing a quick coarse adjustment therefor. The screw 11 is then turned by hand to draw upon the end of the chain connected thereto and thereby tighten the chain around the pile, while the indicator is maintained in proper registry with the mark on the pile. A suitable spirit level is now placed upon the bar 9 and the bracket 2 is adjusted by tilting the same laterally to bring the bar 9 into a perfectly level or true horizontal position, whereupon the pointed end 42 of the screw 40 is pressed into the pile 8 to prevent further lateral tilting of the bracket 2. The spirit level is then placed upon the bar 3 and the screw 40 is manipulated by hand until the bar 3 is adjusted into a perfectly level or true horizontal position.

When the bracket 2 has been thus applied to a pile and adjusted, the saw blade 17 will be level or horizontal and in the same plane with the mark on the pile 8 when the frame 16 is placed upon the bracket 2, as shown in the drawings.

When the bracket 2 is attached to an inclined pile or standard or an inclined portion thereof, the bar 7 is always placed against the lower side of the inclined portion of the pile to which it is applied to prevent gravity action from loosening the chain 14.

After the bracket 2 has been attached to the pile 8, the indicator 35 is turned down

and the frame 16 is placed upon the bracket 2 with the saw 17 at one side of and its teeth 28 facing the pile 8. The pressure fluid is then turned into the motor 18, causing the actuation thereof and the reciprocation of the saw 17. While the saw 17 is being reciprocated, the frame 16 is moved on the pivot pin 29 to pass the saw 17 through the pile 8 to thereby cut the same.

10 When a number of piles or standards are to be cut, two brackets such as 2 may be employed with one frame 16, so that while workmen are manipulating the frame 16 on one bracket applied to a pile to cut the same, 15 other workmen may be applying the other bracket to a pile to receive the frame 16 for the next cutting operation. Thus much time can be saved by applying the frame 16 to the two brackets in alternate succession.

20 While the bracket may be adjusted to cause the saw 17 to make a perfectly level or true horizontal cut, it may also be adjusted to cause the saw 17 to make an inclined cut when desired.

25 I claim as my invention:

1. In a sawing machine, the combination of a bracket, means for attaching the bracket to a standard in different positions of adjustment, a movable saw supported by the 30 bracket and operable to cut said standard, and an adjustable indicator carried by the bracket and movable to a position indicating the plane of movement of the saw relatively to a part of said standard.

35 2. In a sawing machine, the combination of a bracket, means for attaching the bracket to a standard in different positions of adjustment, a movable saw supported by the bracket and operable to cut said standard, 40 and an indicator arm pivoted on the bracket and movable into and from an operative position indicating the plane of movement of the saw relatively to a part of said standard.

45 3. In a sawing machine, the combination of a bracket, means for attaching the upper portion of the bracket to a standard, a movable saw supported by the bracket and operable to cut said standard, the lower portion of the bracket being laterally adjustable

50 relatively to the upper portion of the bracket when it is attached to the standard to vary the angle of the saw laterally, and means carried by the lower portion of the bracket and adapted to engage said standard and to be operated to adjust the lower portion 55 of the bracket toward or from the standard to vary the angle of the saw longitudinally.

4. In a sawing machine, the combination of a bracket, means for attaching the upper portion of the bracket to a standard, a movable saw supported by the bracket and operable to cut said standard, the lower portion 60 of the bracket being laterally adjustable relatively to the upper portion of the bracket when it is attached to the standard to vary the angle of the saw laterally, and a screw adjustably engaging the lower portion 65 of the bracket and adapted to engage said standard and to be operated to adjust the lower portion of the bracket toward and from the standard to vary the angle of the saw longitudinally.

5. In a sawing machine, the combination of a bracket comprising a long, horizontal 75 bar, a downwardly extending bar on one end portion thereof, an inclined brace connecting the other end portion of the horizontal bar and the lower end portion of the downwardly extending bar, and a transverse, horizontal bar extending from the respective sides of the first named bar adjacent to the upper end portion of the second named bar, means to connect the respective ends of the transverse bar to a 80 standard, means on the lower end portion of the downwardly extending bar to engage the standard, a horizontally-movable frame pivoted to the first named bar remote from the second named bar, a horizontal guiding 85 bar secured to the first named bar for supporting said frame between its pivot and the second named bar, and a movable saw guided by said frame and adapted to be operated to cut the standard. 90

95 In testimony whereof I affix my signature hereto.

AARON SANFORD CRAVEN.
